CLAIM

The ornamental design for a lighting fixture, as shown and described.

DESCRIPTION

FIG. 1 is a front right perspective view from below of a lighting fixture according to the new design;

FIG. 2 is an enlarged front right perspective view from below thereof;

FIG. 3 is an enlarged rear left perspective view from above thereof;

FIG. 4 is an enlarged front elevational view thereof;

FIG. 5 is an enlarged right side elevational view thereof;

FIG. 6 is an enlarged left side elevational view thereof; and,

FIG. 7 is an enlarged rear elevation view thereof.

The broken lines in the drawings illustrate portions of the lighting fixture that form no part of the claimed design.

The stippling shown in the figures represent translucent surfaces of the design and does not represent texture or surface ornamentation.

The breakaway lines in the figures indicate a symbolic break in the claimed design. The appearance of any portion of the design between the break lines forms no part of the claimed design.
